UNITED STATES PATENT OFFICE

2,533,881

HEATER

John C. M. Duff, Springfield Gardens, N. Y., assignor of one-half to James Davie, Long Island City, N. Y.

Application January 29, 1948, Serial No. 5,077

4 Claims. (Cl. 126—19.5)

1

The present invention relates to improvements in heaters and more particularly to an improved heater for containers or vessels containing liquids or other substances in which an internal combustion engine provides the source of heat.

In the operation and use of a vehicle it is frequently desirable to heat certain foods or drinks for one or more of the occupants, particularly while on a long trip. Heaters for such liquids and substances have heretofore been proposed which utilized electrical energy from the vehicle battery, or generator, the heat of the engine exhaust and also the heat in the cooling system of the engine. Such prior devices have not found general use for such various reasons as causing an excessive drain upon an already taxed source of electricity, contamination of the food or drink by the exhaust fumes, the inconvenience of its attachment or connection to the heat source or its positioning within or outside of the car. The improved heater of the present invention eliminates these and other objections and inconveniences and is directed to a simple, inexpensive and efficient heater which is preferably mounted in a convenient but unobtrusive position on the fire-wall or other wall surface of the vehicle.

It is a primary object of this invention to provide an improved heater for liquids or substances which derives its source of heat from the cooling system of a vehicle engine. It is a further object to provide such a heater which is of simple and inexpensive construction, and of a unique and compact form and arrangement which does not interfere with the installation of other accessories of the vehicle or with the space required by the occupants. It is a further object to provide an efficient heater construction comprising essentially a central cylindrical receptacle surrounded by a casing of greater height than width such that upper and lower water chamber or headers are formed to thereby eliminate internal baffles.

Another object of the present invention is the provision of an improved heater having a substantially horizontally disposed heating compartment or receptacle into which a closed vessel containing the material to be heated is inserted to thereby prevent contamination or soiling of its contents. It is a further object to provide a heater having a unique quick-opening closure means which engages and resiliently retains the container within the receptacle. A further object resides in providing a heater which is particularly adapted for the heating of a baby's nursing bottle or other container for liquids or food.

2

Other objects and advantages of the present invention will become apparent to those skilled in the art after reading the present description in conjunction with the accompanying drawings forming a part hereof, in which:

Fig. 1 is an elevational view of my improved heater connected to the cooling system of an automobile engine;

Fig. 2 is an enlarged and elevational view of the heater shown in Fig. 1;

Fig. 3 is a partly sectional view of the same as taken along the lines III—III of Fig. 2;

Fig. 4 is a cross-sectional view as taken along the lines IV—IV of Fig. 3.

Referring now to Fig. 1 the numeral 6 represents the outline of a water-cooled automobile engine provided with a radiator 7 and interconnecting water hose connections 8 and 9. The numeral 10 indicates a preferred form of the present heating device which is shown mounted upon the fire-wall or dash-board of the automobile beneath the instrument panel 12 and above the car floor 13. The heater 10, which is hereafter more fully shown in Figs. 2, 3 and 4, is provided with inlet and outlet connections which are connected to the cooling water or other coolant system of the engine 6 by the flexible hose or other conduit sections 14 and 15 respectively.

As shown in Figs. 2, 3 and 4 the heater 10 has an inlet 16 extending through an opening 11a in the fire-wall 11 and an outlet 17 extending through a similar opening in the fire-wall. The heater 10 is formed from a tubular central receptacle 18 forming an inner wall and a surrounding lozenge or diamond-shaped casing of greater height than width forming the outer wall of the heater to create a liquid jacket therein. A similarly lozenge-shaped sheet or plate 20 with a central aperture forms the front wall of the heater and a similarly shaped plate 21 forms the rear wall of the device. The plate 21 is provided with a pair of apertures into which the inlet and outlet 16 and 17, respectively, are welded or otherwise attached. The portions 18, 19, 20 and 21 are preferably formed of suitable metal and are welded, brazed or soldered to each other to provide a water-tight hot-water heater.

A lozenge-shaped cover plate 22 has a rounded periphery 22a and a circular central aperture coinciding with the opening in the end of the receptacle 18 and the end plate 20. The cover plate 22 is also provided with diametrically opposite openings which receive the attachment bolts or rods 23 and 24, which terminate adjacent the

cover plate 22 in the hexagonal heads 25 and 26 respectively and at their opposite threaded ends with the attachment nuts 23a and 24a. The attachment rods 23 and 24 serve to clamp the cover 22 to the heater body and to secure the entire assembly against the fire-wall 11. As may be seen in the cross-sectional view of Fig. 4, the water space within the heater forms upper and lower headers 27 and 28, respectively, which are interconnected by relatively restricted passages or spaces at each side of the central tube 18. This arrangement forms a heating device of relatively high efficiency with a positive and well-distributed flow as indicated by the arrows thereby insuring a continuous transfer of heat to the wall 18 and the central receptacle therein without the necessity of providing expensive internal baffles.

The hexagonal head 25 of the rod 23 is provided with radially aligned holes to receive the ends of the wire 30 of the bottle retaining plate 29. The wire, which may be music wire of suitable diameter, is bent double with a converging pointed portion which is adapted to be snapped over the necked end portion 26a which forms a knob on the hexagonal head of the fastening rod 24. The terminals of the wire 30 are inwardly turned to form a pivot about which the wire clip retainer 29-30 is adapted to be rotated or swung. The numeral 31 represents a baby's nursing bottle which may be inserted horizontally into the receptacle 18 with the base or bottom of the bottle resting against the end wall 21. When filled with cold milk or other fluid to be heated, the bottle is preferably capped with a sanitary flat type nipple 32 against which the plate 29 is adapted to resiliently bear against the nipple and the mouth of the bottle to securely hold the same within the heater until the contents of the bottle reach the desired temperature.

When the heater is first installed or at periodic intervals thereafter the vent valve 33 should be opened to permit the air which may be trapped within the heater to escape and to thereby improve the efficiency and operation of the heater. The casing 19 of the heater may be provided with an insulating jacket indicated by the dotted lines 34, the front edge of which will be retained and covered by the inwardly turned edge of the cover plate 22. Such an insulating jacket will improve the device and reduce the amount of heat radiated from the heater into the car, which heat may be very undesirable in warm weather. Shut-off valves may be provided to shut the heater down when not required or to control the amount of heat carried to it by the car cooling system. If desired the heater may also be provided with a suitable valve by which it may be drained of its contents. The present device can be used to heat the contents of cans or other bottles and is also adapted for installation in long distance busses and other types of motor vehicles. The heated will not interfere with the use of a car heater which may be connected in parallel with the present device. Wherever the term "water" is used herein it will be understood to include any liquid or coolant, which may also contain such anti-freeze ingredients or other improved cooling media used in the cooling systems of vehicle engines. The casing 19 need not be the particular shape which is shown, but may be elliptical or oval shaped in cross-section, and a rectangular form with rounded corners will also provide a satisfactory

shape which will permit of ready installation on the fire-wall beneath the instruments on the dash.

Other forms and modifications of the present invention, both with respect to the general arrangement and the details of the respective parts, which will become obvious to those skilled in the art are all intended to come within the scope and spirit of the present invention as more fully set forth in the appended claims.

I claim:

1. A heater structure of the class described comprising a central horizontal tubular receptacle, an outer casing of greater height than width spaced from and enclosing said receptacle on all but a front end thereof, said casing having a rear wall attached in a water-tight relationship to the rear end of said receptacle, said casing having an apertured front wall, enlarged water chambers formed within said casing by said receptacle above and below the same with restricted passages on each lateral side of said receptacle, hot water inlet and outlet connections passing through said rear wall into said respective water chambers in a diametrically opposed relationship on opposite side of and above and below said central receptacle arranged for the positive circulation without the necessity of baffling of the hot water from said inlet into said upper chamber through both said restricted passages around said receptacle into said lower chamber to said outlet connection, a supporting wall apertured for said inlet and outlet connections, an apertured cover member having an aperture coincident with the front open end of said receptacle and fastening means extending through said cover member and said supporting wall for clamping retaining said casing and receptacle therebetween in an operative position against said supporting wall.

2. A heater structure of the class described comprising a central horizontal tubular receptacle, an outer casing of greater height than width spaced from and enclosing said receptacle on all but a front end thereof, said casing having a rear wall attached in a water-tight relationship to the rear end of said receptacle, said casing having an apertured front wall, enlarged water chambers formed within said casing by said receptacle above and below the same with restricted passages on each lateral side of said receptacle, hot water inlet and outlet connections passing through said rear wall into said respective water chambers in a diametrically opposed relationship on opposite sides of and above and below said central receptacle arranged for the positive circulation without the necessity of baffling of the hot water from said inlet into said upper chamber through both said restricted passages around said receptacle into said lower chamber to said outlet connection, a supporting wall apertured for said inlet and outlet connections, an apertured cover member disposed against the front end of said casing having an aperture arranged to provide access to the open front end of said receptacle, elongated headed fastening means extending through apertures in said covered member and supporting wall for clamping retaining said casing and receptacle therebetween in an operative position against said supporting wall and resilient means pivotally engaging a head portion of a first of said retaining means and releasably engaging a head portion of a second of said retaining means for releasably holding an object to be heated within said receptacle.

3. A heater comprising: a central horizontal cylindrical receptacle; an outer casing of greater height than width spaced from and enclosing said receptacle; front and back end walls attached in a water-tight relationship to the ends of said receptacle and said casing, water chambers formed above and below said receptacle within said casing with restricted passages on each lateral side of said receptacle; and water inlet and outlet connections communicating with said water chambers arranged in a diametrically opposed relationship on opposite sides above and below said central receptacle for the positive circulation of hot water within said casing from a first said water chamber through both said restricted passages about said receptacle and into said second chamber, a supporting wall apertured for said inlet and outlet connections, an apertured cover member having an aperture coincident with the front open end of said receptacle and fastening means extending through said cover member and said supporting wall for clampingly retaining said casing and receptacle therebetween in an operative position against said supporting wall.

4. A heater comprising: a central horizontal cylindrical receptacle; an outer casing of greater height than width spaced from and enclosing said receptacle; front and back end walls attached in a water-tight relationship to the ends of said receptacle and said casing, water chambers formed above and below said receptacle within said casing with restricted passages on each lateral side of said receptacle; and water inlet and outlet connections communicating with said water chambers arranged in a diametrically opposed relationship on opposite sides above and

below said central receptacle for the positive circulation of hot water within said casing from a first said water chamber through both said restricted passages about said receptacle and into said second chamber, a supporting wall apertured for said inlet and outlet connections, an apertured cover member having an aperture coincident with the front open end of said receptacle, fastening means extending through said cover member and said supporting wall for clampingly retaining said casing and receptacle therebetween in an operative position against said supporting wall and resilient means pivotally engaging a head portion of a first of said retaining means and releasably engaging a head portion of a second of said retaining means for releasably holding an object to be heated within said receptacle.
